BOWLING PIN SETTING MACHINE

Journey E. Timberlake, Charlottesville, Va.

Application January 8, 1947, Serial No. 720,787.

23 Claims. (Cl. 273—43)

1

This invention relates to a mechanical pin setter for use with bowling alleys.

In recent times it has become increasingly difficult to secure labor for setting pins in bowling alleys and it has also become necessary to pay those engaged in the occupation increasingly higher wages. The result of this condition is, of course, to cut the profit of bowling alley owners excessively and to increase the price which users of the alleys must pay for the privilege. It has become increasingly evident that the only immediate solution to the difficulty is the provision of mechanical pin setting equipment to take the place of the human pin setter.

Mechanical pin setting equipment, besides having the advantage of lowering the cost per game of the sport, also provides an added inducement for the customers who are fascinated by the idea of the bowling pins being set by purely mechanical means. Particularly in the case of the present device, as will be brought out in detail in the description of the apparatus, the part which the bowler takes in operating the pin setting equipment increases even more the fascination which the equipment has.

Several attempts have been made in the past to provide mechanical pin setting equipment but for the most part the prior devices are of such a complicated nature that both the initial cost and the maintenance cost are prohibitive.

It is a primary object of this invention to provide a pin setting mechanism which overcomes the above-described difficulties.

It is another object of the invention to provide a pin setting mechanism which may be controlled from a remote point, such as the bowlers' end of the alley, whereby the operator is able to control at will the operation of the machine.

A further object of the invention is to provide a mechanical pin setter having a novel combination of mechanical, electrical and fluid operated interlocks to assure the correct operation of the machine.

Still another object of the invention is to provide in a mechanical pin setter, a novel apparatus for distributing the pins, novel means below the level of the alley for receiving the pins as they are set, novel means for sweeping pins from the alley and novel means for assuring that the pins are correctly oriented before they reach the apparatus which distributes the pins.

These and other objects of the invention will be apparent from the following specification and the accompanying drawings, in which:

Figure 1 is a side elevational view of the mecha-

Figure 37 is a detail side elevation of a modified version of the mounting of the bridge-like framework at the front of the machine, and

Figure 38 is an electrical diagram of a modified electrical circuit for the machine.

In order to facilitate the understanding of the operation and construction of the apparatus a brief summary of the device will be helpful at this point. In general, the apparatus comprises a mechanism located at the rear of a bowling alley which, under the control of the operator, for instance, the bowler, sweeps the pins from their positions at the rear of the alley into a sloping walled hopper which also receives the bowling balls. The pins and balls pass from the hopper to an endless conveyor known as the sub-conveyor which carries the pins and balls through a device which removes the balls and directs them to a trackway-like device upon which they roll back to the bowler at the forward portion of the alley.

The sub-conveyor carries the pins either base up or base down and a novel mechanism is provided at the upper end of the sub-conveyor

for orienting the pins after which they fall base first into a chute which guides them to the main conveyor.

The main conveyor carries the pins with their bases bottommost to an elevated position where they fall into a chute which serves both as a storage place for the pins and as a means for guiding the pins to a rotary distributor.

The rotary distributor is carried by a movable carriage which may be moved between a forward position a substantial distance toward the front of the alley from the portion of the alley upon which the pins are set, and a rearward position directly over the pin receiving portion

15 of the alley. The rotary distributor is provided with a plurality of pin receiving compartments and is alignable with a plurality of chutes which are part of the movable carriage. When the carriage is in its forward position, the rotary distributor is rotated constantly so that any empty pin receiving compartments receive pins, one to each compartment, from the chute which extends from the upper end of the main conveyor.

20 25 When the carriage is moved to its rearward position for the purpose of setting pins, sliding doors positioned one at the upper end of each of the chutes carried by the movable carriage, are opened so that pins may fall from the compartments in the rotary distributor through the chutes in the movable carriage for setting.

When the pins fall from the chutes of the movable carriage, they fall into pin receivers which are located below the level of the alley, one pin receiver being positioned at each of the ten spots upon which the pins are set. The upper ends of the pin receivers are normally flush with the upper surface of the alley but when the receivers are extended upwardly to receive pins from the movable carriage, the pin receivers form cup-like devices which receive the pins and then lower the pins to their set positions on the alley.

When the bowler has bowled a ball and wishes

45 to clear "dead wood," that is, fallen pins, from the alley, and thereafter to reset the pins which have remained standing, he operates a control

46 which causes the movable carriage to move rearwardly carrying with it a sweep which is lowered by the first portion of the rearward movement

47 of the carriage and which sweeps the pins from the alley during the rearmost portion of the rearward movement of the carriage. With all

48 of the pins swept from the alley, the bowler then operates the control devices to set those of the pins which he wishes to replace, whereupon the

49 proper pin receivers are moved upwardly out of the floor and the proper sliding doors in the

50 movable carriage open to permit pins to fall into the receivers. The bowler then operates

51 the control devices again to cause the pin receivers to return to their positions flush with the floor, carrying with them the pins which are

52 to be set, and cause the movable carriage to return to its forward position. The forward

53 movement of the carriage lifts the sweep clear of the alley, and when the carriage reaches its forward position, the rotary distributor automatically begins to receive pins from the storage

54 chute to replace those pins which have been set.

55 Two or preferably three full sets of pins are used with each alley to assure a ready supply of pins at all times.

56 The apparatus includes a novel interlocking arrangement of pneumatic means, electrical ap-

paratus, and other control devices for assuring the proper sequence of operations of the device.

To proceed now with a detailed description of the apparatus as shown in a preferred embodiment in the drawings, the supporting framework for the device includes downwardly extending members 50 which are supported from the ceiling of the establishment and which support a pair of longitudinal frame members 51 which carry tracks 52 (Figures 6 and 10), the purpose of which will be described presently. Other frame members 53 are positioned above the rear end of the alley, the bowling surface of which is indicated by the numeral 54. Upwardly extending frame members 55 mounted on the floor of the establishment support the various parts of the conveyor system as will be described in detail presently. The longitudinal frame members 51 may be supported from the floor if desired, instead of from above.

The conveyor system

At the rear end of the alley, as shown in Figure 1, there is provided a sloping walled depression or hopper 60 which has a rear wall 61 padded, if desired, and having an opening at its lower end to permit passage of pins and the balls therethrough. Referring now to Figure 25, the pins and balls pass from hopper 60 onto a slanting wall 62 which guides them into contact with the lower end of the sub-conveyor which is denoted generally by the numeral 63. The upper portion of wall 62 is slanted toward the conveyor 63, the ball and pin receiving portion of which extends at an angle to the vertical away from wall 62. The lower portion 64 of wall 62 extends at an angle to the upper portion of wall 62 and is generally parallel to the path of travel of the sub-conveyor 63 so that pins falling into the space between wall portion 64 and the sub-conveyor become aligned with the sub-conveyor and are picked up thereby. The distance between the wall portion 64 and the sub-conveyor is slightly smaller than the diameter of a bowling ball so that the balls do not fall into this space but are picked up by the conveyor at the point where the wall 62 begins to slope away from the conveyor.

The sub-conveyor

The conveyor 63 comprises a pair of spaced metallic link belts 68 provided with transversely extending pick-up members 69 which, as shown in Figure 26, have a broadened central portion 70 and which are spaced apart a distance substantially greater than the length of a bowling pin.

Link belts 68 pass over upper sprockets 70a and lower sprockets 71, being driven from the lower sprockets 71 which in turn are driven by means which will be described presently.

A rounded sheet metal guide member 72 (Figures 1 and 25 through 28) is positioned adjacent and parallel to the underside of the upper stretch of sub-conveyor 63 so that pins, as shown at 73 in Figure 27, rest on cross links 69 of the conveyor and slide along the guide member 72 in their upward travel in the sub-conveyor. It will be apparent from the Figures 26 and 27 that the link belts 68 of the sub-conveyor are separated by a distance slightly greater than the largest diameter of a pin. The diameter of a bowling ball is slightly greater than the distance between the two link belts 68 of the sub-conveyor and this difference in diameter is taken advantage of in re-

moving the balls from the sub-conveyor during their upward movement therein.

The removal of the balls from the sub-conveyor is accomplished as shown in Figure 28, there being shown therein in solid lines a ball 76 resting against the two link belts of the sub-conveyor and against one of the cross members 69 of the sub-conveyor. Cam-like deflectors 77 are positioned adjacent the upper surface of each link belt 68 along the path of upward movement of the belt and near the upper sprockets 70a. The trackway 80 which returns the balls to the bowler extends to a point near the lower ends of the cam-like deflectors 77 and has a transversely directed portion having side walls 81 which extend to points on each side of the sub-conveyor near the deflectors 77. The floor of the transversely directed portion of the trackway comprises a flexible piece of fiber board or other similar material as denoted by the numeral 82 and extends toward the sub-conveyor to a point separated from the sub-conveyor by a distance less than the diameter of a bowling ball. An end portion 83 of floor member 82 is cut out in a circular manner to facilitate passage of an upwardly moving ball past the member 82 which bends upwardly to permit passage of the ball and then resumes its normal substantially horizontal or slightly tilting position after the ball is moved above it.

After a ball has moved past floor member 82 to the broken line position of Figure 28 and continues moving upwardly, the deflectors 77 remove the ball from the sub-conveyor in the manner shown by the broken-line balls of Figure 28, the ball falling onto floor portion 82 and passing from there to the trackway 80 by which it is returned to the bowler in a conventional manner.

Returning now to the pins which are being carried upwardly by the sub-conveyor in the manner shown in Figures 26 and 27, it will be noted that because of the previously described arrangement at the bottom of the sub-conveyor, some of the pins are picked up by the sub-conveyor with their base uppermost as in the case of pin 73 while others are picked up with their base bottommost as in the case of pin 73a of Figure 27.

As it is desired that all of the pins pass to the main conveyor, which will be described presently, with the base of the pin bottommost, a novel pin orienting device is provided at the upper end of the sub-conveyor which now will be described.

The pin orienting means

As shown in Figures 1, 3, 4, 26 and 27, the pin orienting device comprises a U-shaped member 90 pivotally mounted a short distance above sprocket wheel 70a on an upstanding frame member 91. An arm 93 carrying a weight is fixed to the end of portion 92 of U-shaped member 90; arm 93 being positioned at an acute angle relative to the curved portion of the U-shaped member 90 in a rest position extended downwardly at a small angle from the vertical.

As shown in Figure 27, the U-shaped member 90 is spaced a sufficient distance above sprocket 70a so that a pin such as pin 73a moving upwardly in the conveyor with its neck uppermost reaches a position in which the neck of the pin rests in the curved portion of U-shaped member 90 and, as the pin is carried further upwardly by the sub-conveyor, the member 90 pivots to the dotted line position shown in Figure 27 with the neck of the pin still supported by the curved portion of the pin member 90. As the pin passes dead center

as shown by dotted lines in Figure 27, it falls base bottommost into a chute 94 which curves to the rear of the sub-conveyor as shown in Figure 1 to carry the pin to the main conveyor which is yet to be described.

In the case of a pin such as pin 13 of Figure 27 moving upwardly in the sub-conveyor with its base uppermost, it will be clear from the figure that the spacing of member 90 permits the pin to move base uppermost over the top of sprocket wheel 70a without being affected by member 90, the pin falling base down into chute 94 for passage to the main conveyor.

The main conveyor

The main conveyor will now be described with reference to Figures 1, 3, 4, 24 and 29. In general construction the main conveyor is similar to the sub-conveyor as it comprises a pair of metallic link belts 100 spaced apart a distance slightly greater than the largest diameter of the pin and provided at spaced intervals with transversely extending pin supporting members 101 as in the case of the sub-conveyor previously described. Chains 100 run over freely running lower sprocket wheels 102 and 103 carried by appropriate shafts mounted on a portion of the rear frame of the device in an appropriate manner. As the details of the mounting of these sprocket wheels do not comprise any part of the invention and as they may be mounted in any conventional manner, the mounting brackets are omitted in portions of the drawings to facilitate a clearer showing of more important details of the invention.

At the upper end of the main conveyor, chains 100 (Figures 3 and 4) run over sprocket wheels 105 which are fixed to a rotatably mounted shaft 106 supported by brackets 107. Shaft 106 also carries a wheel 108 which is driven by a belt and pulley arrangement 109 from an electric motor 110 supported by transverse frame member 53. In this manner motor 110 rotates wheel 108 and thereby rotates shaft 106 and sprocket wheels 105 to drive the main conveyor and move the endless belts 100 thereof counterclockwise as viewed in Figures 4 and 24.

Sheet metal guide members 112 positioned about the upwardly moving parts of chains 100 provide a guideway for the upwardly moving pins, the upper end of the outer member 112 extending a short distance above the upper sprockets 105. Members 112 terminate at their lower ends a short distance above the point at which chute 94 feeds pins to the main conveyor. Lower pin receiving guide 113 (Figure 4) partially surrounds the lower portion of the upwardly moving portions of chains 100 and is positioned so as to receive pins from chute 94 and guide the pins into contact with transverse members 101 of the main conveyor. There need be no bottom or detent in the interior of guide 113 due to the fact that the spacing of transverse pin supporting members 101 of the conveyor is such that one of the members 101 reaches the lower end of guide 113 by the time the next preceding member 101 leaves the upper end of guide 113. This, of course, is also a question of the length of guide 113.

At the upper end of the main conveyor a pin deflector 115 (Figure 29) mounted on a vertically extending frame member 116 extends transversely at an angle above the upper end of the conveyor so as to leave a space between deflector 115 and upper sprocket wheel 105 sufficiently large

to permit passage of a pin lying on its side. As shown in Figure 29, as a pin 117 reaches the upper end of the main conveyor, it strikes deflector 115 and as the chain continues moving, the base of the pin is carried over the top of sprocket 105 while the upper end of the pin is held against moving by deflector 115. This causes rotation of the pin from a vertical position to a more or less horizontal position and permits the conveyor to carry the pin in this horizontal position in the direction of movement of the chain that is to the left as viewed in Figure 29. As the pin passes over the upper end of the conveyor it falls into a forwardly extended guide chute 118 provided in its bottom with rollers 119 or other friction decreasing means, and which serves to guide the pin to the rotary distributor which will be described in detail presently.

Returning now to lower sprocket 103 of the main conveyor, this sprocket is keyed to a shaft 121 which drives a transversely extending link belt 122 by means of a rearwardly positioned sprocket 123 (Figures 4 and 24). Belt 122 runs over appropriate sprockets 124 and cooperates with a sprocket 125 which drives another sprocket 126. Sprocket 126 drives a belt 127 which transmits rotary movement to sprocket wheel 128 keyed to a shaft 129 to which are also keyed lower sprocket wheels 71 of the sub-conveyor. In this manner motor 110 drives the sub-conveyor through the medium of the main conveyor and the belt and pulley connection 109.

It might be well to point out at this time that according to the preferred embodiment of the invention described herein, the conveyor system is set into motion when the alley is to be used and continues running continually until turned off at the termination of use of the alley, such as at the time a bowler discontinues the game or at the close of business each day. Other types of conveyors can be used with the machine if desired and I do not wish to be limited to the particular conveyor system I have described.

The movable carriage and rotary distributor

Chute 118 which has been described previously and which receives pins base downward from the upper end of the main conveyor serves both as a means for guiding the pins to the rotary distributor and as a storage place for pins when the rotary distributor is full. Inasmuch as more than the ten pins set at any one time and preferably three full sets or 30 pins are used with the machine, it is not unusual for there to be several pins stacked in chute 118.

The rotary distributor designated generally by the numeral 140 comprises a circular sheet metal drum slightly deeper from top to bottom than the length of a bowling pin, and having ten circularly disposed pin-receiving openings or compartments 141 extending vertically therethrough. The distributor 140 is mounted for rotation about its center by means of a suitable pivot bolt 142 which extends downwardly through the center of the distributor and is supported by a flat wooden or sheet metal member 143 which comprises the upper side of a movable carriage designated generally by the numeral 145.

The movable carriage has a flat lower member 146 which is suspended a considerable distance below upper member 143 by means of vertically extending rods 147. The upper and lower members 143 and 146 are rectangular in shape and the four rods 147 are positioned one at each corner of the carriage.

The upper member 143 of the movable carriage has ten openings 149 which are positioned in a circle and are adapted to be aligned with the pin-receiving compartments 141 in the rotary distributor when the distributor is at rest as will be described more completely presently. Pin-guiding chutes 150 extend from the openings 149 downwardly almost to the upper surface of lower carriage member 146 where they are aligned with ten openings in member 146.

The openings in member 146 instead of being in a circle as are openings 149, are positioned in the configuration which the pins will have when they are finally set upon the upper surface of the alley, and it is, of course, necessary that certain of the chutes 150 deviate from the vertical as is shown in Figures 1, 2 and 4.

The lower ends of chutes 150 each carry four pin-aligning and retarding arms 154 (Figure 14) which are fixed to the chutes at their upper ends 155 and are urged inwardly by springs 156 positioned on guide rods 167 which extend radially outwardly from the outer surfaces of the chutes 150 near their lower ends. When the pin-aligners 154 are in their normal positions, the openings through their inwardly bent lower ends are smaller than the diameter of the base of a bowling pin but are slightly larger than the diameter of the rounded upper end of a bowling pin so that as a pin falls downwardly through one of the chutes, in a manner which will be described presently, its momentum causes the base of the pin to spread arms 154 against the tension of the springs 156 so that the pin passes through the pin aligner 154 and drops into one of the pin-setters or receivers which will be described presently. The spreading of arms 154 against the tension of springs 156 retards the downwardly moving pin so that it does not bounce out of the pin receiver below it. When a pin is halted in its downward movement by one of the pin-setters or receivers, its upper end or neck extends into the opening between the aligning members 154 so that the pin is steadied and positioned in the exact center of the pin-setter or receiver. The resiliently mounted pin aligning members 154 also tend to prevent any rebound upwardly of the pins after they fall into the pin-setter or receiver.

Upper member 143 of the carriage is positioned between the aforementioned tracks 52 (Figures 4, 5 and 6) and is suspended from said tracks by means of four vertically extending rods 160 attached to the ends of transverse pieces 143a fastened to the underside of member 143 and extending beyond its side edges. Each rod 160 carries a transverse shaft 161 upon the ends of which, and on either side of rod 160 are a pair of rollers 162. The tracks 52 are rectangular in cross section and are provided with longitudinally extending slots 163 down their centers which are wide enough to permit the passage therethrough of rods 160 but are narrow enough to leave horizontal track portions 164 on either side thereof upon which the rollers 162 ride.

The movable carriage 143 is moved by means of two endless link belts 170 which are positioned on either side of the carriage and supported by forward sprockets 171 and rear sprockets 172 mounted on the longitudinal frame members 51 of the device. The two rear sprockets 172 are keyed to a transverse shaft 173 so as to rotate together and thereby to assure that the two belts 170 move in coordination. Another sprocket wheel 174 is keyed to shaft 173 and is

driven by a belt 175 which is rotated through an appropriate pulley arrangement 176 by a reversible electric motor 177.

The outer end surfaces of cross pieces 143a of the carriage abut the inner surfaces of side members 179a (Fig. 10) to which are attached the lower ends of V-shaped brackets 179 which are attached at their upper ends at 180a to the lower courses of belts 170 so that the carriage is moved by the belts 170.

When it is desired to move the carriage from the forward position in which it is shown in Figure 1 to the rearward position in which it is shown in Figure 2, the motor 177 is rotated in one direction by means of a control system which will be described in detail presently, to move the belts 170 in a counterclockwise direction as viewed in Figure 1. When it is desired to move the carriage from the rearward position to the forward position, the motor 177 is rotated in the opposite direction so as to drive belts 170 in a clockwise direction as viewed in Figure 1.

Referring now to Figures 5 through 7, 11 and 12, the pin-receiving compartments 141 in the rotary distributor 140 are normally separated from the upper ends of the chutes 150 by means of sliding doors 180 carried by the upper surface of the upper carriage member 143 and slidable between guides 181 (one of which is shown in Fig. 7) which lie in the plane of doors 180 on upper carriage member 143. Doors 180 extend a substantial distance beyond the outer periphery of the drum-like rotary distributor 140, the outwardly extending portion of each door 180 being provided with two upwardly extended projections 182 and 183.

Projection 182 is engaged by an arm 184 (Fig. 11) which is mounted on a rotatable shaft 185 which is positioned above and parallel to upper carriage member 143 and transversely to the direction of movement of its doors 180. Upwardly extending brackets 186 mounted on the upper surface of carriage member 143 on either side of each of the doors 180 serve to support shaft 185 and thereby to support pivoted arm 184. A helical spring 187 surrounds a portion of shaft 185 and is attached at one end to one of the bracket members 186 and at the other end to arm 184 so as to urge arm 184 to the position shown in Figure 11 in which, by the engagement of arm 184 with projection 182 of door 180, the door is urged to its normal closed position as shown in Figure 11. It will be apparent that each door 180 may be moved outwardly relative to its normal position against the tension of spring 187 and that the spring 187 acting through arm 184 will thereafter restore door 180 to its normal closed position when the door is released.

The means for opening each door 180 comprises a pneumatic cylinder 190 supported in a vertical position below upper carriage member 143 by a bracket 191 at a point spaced a short distance beyond the limit of outward movement of its door 180. As shown in detail in Figure 12, each cylinder 190 has an air inlet 192 at its upper end and has an interior piston 193 connected by means of a piston rod 194 with a transverse arm 195 to which are attached a pair of connecting rods 196 which lie on either side of cylinder 190 and parallel thereto. At their upper ends rods 196 are attached to a cross arm 197 provided with a hook or eye 198 for attachment of one end of a short length of cable 199. Cable 199 is attached at its other end to projection 183

on the outer end of door 180 and intermediate its two ends passes over a grooved roller 200 carried by a plate 201 which is attached by suitable means such as screws (not shown) to the underside of upper carriage member 143. Each roller 200 projects upwardly through an opening 202 in the carriage member 143 so that its highest point is approximately level with the upper surface of member 143. It will be apparent that when air under pressure is passed through port 192 into the upper end of cylinder 190, the piston 193 will be forced downwardly causing a corresponding movement of cable 199 which in turn pulls the associated door 180 radially outwardly with respect to the rotary distributor to an open position permitting a pin positioned within the corresponding pin-receiving compartment 141 to pass downwardly out of compartment 141 into the chute 150 aligned therewith. The details of the pneumatic system of the apparatus will be described presently.

It will be understood that each of the upper ends of chutes 150 has a door 180 normally closing the upper end of each chute 150 and that for each of the doors 180, ten doors in all, there is a complete operating mechanism as shown in Figures 11 and 12 so that each door may be operated independently as desired by admitting air under pressure to the appropriate cylinder 190. In order to avoid over-elaboration of the accompanying drawings, all ten of the doors 180 are not shown but instead only one door is shown in each of the various appropriate figures with the understanding that there are ten of the doors and door-operating mechanisms as described above.

The means for indexing the rotary distributor and for controlling the movement of the pins into the rotary distributor

As described previously herein, the pins carried by the conveyor system to the chute 118 move downwardly base first in the chute under the influence of gravity toward the rotary distributor 140, assuming that the rotary distributor and the movable carriage 145 are in the forward position. In order to insure orderly admission of a bowling pin into each of the pin-receiving compartments 141 of the rotary distributor 140, the mechanism shown in detail in Figures 5 through 7 has been provided.

This mechanism is mounted on a bridge-like supporting framework consisting of short upwardly extending frame members 210 carried by longitudinal frame members 51 and supporting transverse framework members 211. The framework consisting of members 210 and 211 lies above the forward position of the movable carriage 145 and rotary distributor 140 and members 211 are sufficiently elevated above main frame members 51 to provide clearance for rotary distributor 140 so that the distributor can move to its loading position beneath the bridge-like framework.

Supported on one of the rearwardly positioned transverse frame members 211 is an electric motor 213 which drives a longitudinally extending shaft 214 through a pulley and reducing gear arrangement 215. Shaft 214 is supported above the bridge-like framework by appropriate supporting brackets 215a and serves as a means of transmitting rotary motion from motor 213 to several mechanisms carried by the bridge-like framework.

One of these mechanisms driven by motor 213

through shaft 214 is a device for indexing rotary distributor 140 so that each time the rotary distributor is indexed, each pin-receiving compartment 141 is moved to a position above the next door 180 in its path of travel, and the compartments 141 are moved successively under the forward end of chute 118.

Near the forward end of shaft 214 a disc 217 is keyed to the shaft and is maintained in a fixed position on the shaft by suitable means such as set screws or collars (not shown). A bar 218 is mounted transversely of the apparatus for sliding movement in guides 219a carried by a pair of the upwardly extending framework members 210. Bar 218 is longer than the distance between oppositely positioned framework members 210 so that when reciprocated in the direction of its length (transversely to the alley) it still remains supported by the guides 219a. Bar 218 carries 15 a U-shaped attachment 219 which clamps about the bar and is tightened thereon by means of a screw 220. The lower portion of member 219 carries a downwardly extending arm 221 pivotally attached to the member 219 and held against rotation in a counterclockwise direction as viewed in Figure 6 by means of a downwardly extending projection 222 carried by the underside of member 219. Arm 221 is free to rotate in a clockwise direction as viewed in Figure 6 and always tends to return to its normal downwardly extending position in which it is shown in Figure 6 under the influence of gravity, or, if desired, a spring (not shown).

A crank arm 224 is attached to disc 217 near its periphery and another similar arm 225 is pivotally attached to member 219. To provide a driving connection between arms 224 and 225, there are provided a pair of cross members 226 and 227 each of which is provided with two holes, 35 one of which holes receives arm 224 and the other of which receives arm 225. Cross member 226 is fixed to arm 224 by means of a pin 228 and is not attached to arm 225 so that arm 225 is free to reciprocate within one of the holes in cross member 226. The arrangement of cross member 227 is just the opposite, that is, it is pinned to arm 225 by a pin 229 and slidably receives the lower end of arm 224. A helical spring 230 surrounds the portion of arm 224 which lies between cross members 226 and 227 so as to tend 40 to maintain these cross members separated. It will be apparent that as disc 217 is rotated by shaft 214, arm 224 is reciprocated and transmits a similar motion to arm 225 by means of the 45 resilient connection therebetween. The reciprocation of arm 225 reciprocates member 219 and rod 218.

Around its outer periphery and near its upper edge, the rotary distributor 140 is provided with 50 radially extending indexing projections 232 at regularly spaced intervals, the arrangement being such that the reciprocation of bar 218 brings downwardly extending arm 221 into indexing contact with one of the indexing projections 55 232 during each movement of the bar 218 to the left as viewed in Figure 6. Upon return movement of the bar to the right in Figure 6, the arm 221, due to its ability to pivot in clockwise direction freely, rides up over the next indexing projection 232 so that upon the next succeeding leftward movement of bar 218, the arm 221 engages the next projection 232 on the rotary distributor and moves the distributor through an 60 arc sufficient to move each pin-receiving com-

partment 141 to a position above the next succeeding reciprocating door 180.

The pins which move downwardly in chute 118 toward the rotary distributor pass into the pin-receiving compartments 141 of the rotary distributor one at a time and suitable means are provided for assuring that when one of the pin-receiving compartments 141 contains a pin, another pin will not remain partially in the compartment during indexing of the rotary distributor in such a manner as to jam the apparatus. The preferred mechanism for accomplishing this is shown in detail in Figures 7 and 13. As shown in Figure 7, a sprocket wheel 240 is keyed to shaft 214 and by means of a belt 241 rotates a shorter shaft 242 which extends in a direction longitudinally of the alley and is carried by appropriate supports 243 extending upwardly from transverse frame members 211 of the bridge-like supporting framework. At the rear end of shaft 242 is another sprocket 244 which drives a link belt 245 which passes over a sprocket 246 carried by another short shaft 247 similar to shaft 242, and positioned on the opposite side of the center line of the apparatus.

Each of the shafts 242 and 247 carries an eccentric cam 248, each of which cams cooperates with the upwardly bent end portions 249 of transversely movable doors 250. The doors 250 extend through the side walls of a funnel-like pin guiding member 251 and at their outer ends are attached to springs 252 which are attached to the upper portions of the funnel-like member 251 at 253. Springs 252 tend to pull the sliding doors 250 inwardly to a closed position from the open position in which they are shown in Figure 13. However, as the shafts 242 and 247 rotate the cams 248 to the position shown in Figure 13, the doors 250 are forced to the open position to permit passage of a pin downwardly therethrough. The inner ends of doors 250 are bent downwardly through a 90 degree arc at 255 so that if the inwardly curved bottom portion of a pin is positioned therebetween due to its resting on a pin which has already entered one of the pin receiving compartments 141, the curved inner portions 255 of the doors 250 slide along the curved bottom portion of the pin and force the pin upwardly permitting the doors 250 to close completely. This assures that a pin does not lie half in and half out of a compartment 141 during indexing of the rotary distributor and thereby prevents jamming.

The opening and closing of doors 250 is so co-ordinated with the operation of the indexing device for the rotary distributor which has been previously described that the rotary distributor is indexed only when the doors 250 are closed, and the doors 250 open only when the rotary distributor is at rest with one of the pin-receiving compartments 141 positioned directly below the reciprocating doors 250. This co-ordination of the operation of the two mechanisms is simple due to the fact that they are both driven from the same shaft 214.

Another mechanism is provided for assuring the orderly movement of pins into the funnel-like member 251, this apparatus being shown in detail in Figures 7 through 9. A longitudinally extending shaft 260 is mounted above the bridge-like framework previously described and is positioned on the opposite side of the central line of the machine from shaft 214. Shaft 260 is driven by shaft 214 by means of sprockets 261 and a belt 262. At its rear end, shaft 260 car-

ries a cam 263 upon which rides a rotatable cam follower 264. The cam follower 264 is carried by a pair of short longitudinally extending rods 265 and is biased toward cam 263 by means of a spring 266 anchored to one of the upwardly extending arms 267 which support shaft 260.

The two shafts 265 are spaced apart a short distance by means of a forward cross-arm 268 and carry a pair of slidable cross-arms 269 which normally are maintained mid-way along the length of rods 265 by means of helical springs 270 positioned about rods 265 on each side of cross-arms 269. Springs 270 bear at the forward ends of the rods against cross member 268 and at the rear ends of the rods against nuts 271.

A transverse shaft 273 is supported at the forward end portion of the chute 118 by means of upwardly extending arms 274 mounted on the previously described bridge-like framework. Shaft 273 also extends above rods 265 and is provided with a downwardly extending arm 275 which is movable with shaft 273 and which extends at its lower end in between cross-arms 269. The portion of shaft 273 which lies directly over the center line of chute 118 carries an arcuate pin movement regulating member 276 which is bowed downwardly and which oscillates with shaft 273. The arcuate shape of member 276 roughly conforms to the bulbous shape of the large lower part of a bowling pin.

It will be clear that rotation of shaft 214 rotates shaft 260 which in turn rotates cam 263. Rotation of cam 263 imparts a reciprocatory movement to rods 265 which by means of springs 270 reciprocate cross-arms 269 and oscillate arm 275 carried by shaft 273. This, of course, results in an oscillatory movement of the pin movement regulating member 276.

Member 276, due to its shape and its position in the path of pins passing down chute 118, prevents movement of pins when it is at either extreme of its movement, in the following manner. When the member 276 tilts with its rear end upwardly, a pin above the member can slide downwardly until its enlarged base lies beneath member 276, at which time the lower part of the base of the pin is stopped by the depressed front end of member 276. As the member 276 then moves its rear end downwardly and its front end upwardly, the pin under the member moves down to the two doors 250 assuming there is no other pin between the doors and the member 276. If there is a pin resting on doors 250, the pin under member 276 cannot move downwardly and therefore it stays approximately in place and its base is again engaged by the front end of member 276 when the member moves to its rear end-up position. Because of the small neck of the pin, the rear end of the member 276 can move downwardly with a pin under the member without affecting the pin. Assuming the pin under member 276 moves into contact with doors 250 when the front end of member 276 is raised, then the next pin above in the chute slides under member 276 when the rear end of member 276 is again raised.

Member 276 is positioned relative to doors 250 in such a manner that if there is a pin resting on doors 250, the contact of a pin under member 276 with the pin resting on doors 250 maintains the pin under member 276 in such a position that its base will be again engaged by the front end of member 276 if the pin on doors 250 does not pass into a compartment 141.

The oscillation of member 276 is timed with

the opening and closing of doors 250 by obvious means since both member 276 and doors 250 are operated from shaft 214. The timing is such that when doors 250 are open, the rear end of member 276 is elevated, and when doors 250 are closed, the front end of member 276 is elevated. This arrangement assures that the weight of all of the pins in chute 118 does not rest on the doors as this would tend to overcome and prevent the camming of a pin upwardly by the closing movement of doors 250 when there is a pin in the compartment 141 below the doors, as has been explained above. Thus only one pin at a time rests on doors 250 and no more pins move past member 276 until the pin resting on doors 250 falls through them and passes completely into one of the compartments 141 of the rotary distributor.

The pin receivers

When the pins carried by the rotary distributor are released for passage downwardly through chutes 150 by the opening of doors 180, the pins fall into pin receivers which are normally located below the level of the floor of the alley, and which are raised to a pin-receiving position as shown in Figure 2 by means which will be described presently. Referring now to Figures 1, 2 and 19 through 23, a framework is shown in detail in Figures 19 and 20 consisting of upright members 280, longitudinal members 281 and transverse members 282, all of the frame members being conveniently of angle iron and welded or bolted together to form a substantial structure. The framework is supported on a flat base plate 283 provided at each of its four corners with jack screws 284 which provide means for adjusting the level of the base plate 283.

Below the ten positions at which the pins are to be set at the rear of the alley, base plate 283 is provided with ten threaded studs 285 welded to the base plate and extending upwardly a short distance thereabove. Fitting loosely over each of the studs 285 is an adjusting plate 286 provided with a central opening 287 for receiving stud 285. Adjusting plates 286 are only slightly larger in diameter than the pin receivers which are to be described presently, plates 286 each being provided with four jack screws 288 positioned at the four corners of a square and bearing against the upper surface of base plate 283 so as to provide means for adjustably tilting plate 286 relative to base plate 283.

Each of the plates 286 supports a hollow cylindrical pin-receiver core 290 welded at its bottom to a disc 291 having a central threaded opening adapted to be engaged by the threaded portion of stud 285. The upper portion of each disc 291 has a pair of diametrically oppositely positioned projections 292 which may be engaged by a long handled wrench (not shown) for turning the core 290 relative to stud 285 to remove the core or place it in position.

Each of the cores 290 extends vertically upwardly to a point a short distance below the upper surface 294 (Figure 21) of the alley and is surrounded by a slightly larger hollow cylindrical sleeve 295 which is slightly shorter than core 290. Sleeve 295 is free to move relative to core 290 and carries at its upper end a shorter sleeve 296 which is sufficiently larger in diameter than sleeve 295 to fit about the outside of sleeve 295 for attachment thereto as by welding or other suitable means. The upper end of sleeve 296

lies flush with the surface of the alley when sleeve 295 is in its lowermost position.

A wooden disc 297 normally rests on the upper end of core 290 and is of such a thickness that its upper surface is flush with the surface of the alley when it is at rest on core 290. The diameter of disc 297 is only sufficiently smaller than the interior diameter of sleeve 296 to permit relative movement between the two parts. 5 It will be apparent from Figure 21 that when sleeves 295 and 296 are elevated to the pin-receiving position shown in Figure 2 by means which will be explained presently, the shoulder formed by the upper end of sleeve 295 will move 10 upwardly and pick up disc 297 so as to lift the disc off of the upper end of core 290 and carry the disc upwardly with sleeves 295 and 296. The cup-like opening provided in this manner within 15 the sleeve 296 and above the upper surface of disc 297 serves to receive a pin which has passed downwardly through one of the chutes 150. When the sleeves 295 are again lowered to their 20 normal positions below the surface of the alley, the pin which has been dropped into the pin receiver remains standing on the upper surface of disc 297 in its proper set position, the upper surface of disc 297 being flush with the surface of the alley as has been explained previously.

Referring to Figures 21 and 22, each of the 25 sleeves 295 has a rack-type gear 300 extending along most of its length and serving as part of the means for elevating the pin receiver. The uppermost longitudinal framework members 281 support ten transverse shafts 303, each of which 30 carries a pinion gear 304 positioned to engage the rack 300 of the adjacent pin receiver. Each shaft 303 also carries a pulley wheel 305 to which is attached a cable 306, the lower end of which is attached to a counterweight 307. From Figure 21 it will be clear that the rotation of shaft 303 and pinion gear 304 in the counterclockwise direction to raise the pin receiver will be assisted by the counterweight 307 which partially balances the weight of sleeves 295 and 296 and the disc 297 which are raised by rotation of shaft 303.

Certain of the shafts 303 also carry a sprocket wheel 308 adapted to be rotated by means of a belt 309. Belts 309 are driven by other transversely extending shafts 310 which are supported 45 at various points by longitudinal frame members 281, and which extend toward the left side of the framework looking from the bowler's position toward the rear of the alley.

At their left ends, each of the shafts 310 is 50 provided with a sprocket wheel 311 which is rotated by belt and chain means which will be described presently. It will be noted from Figures 19 and 20 that certain of the shafts 303 extend past the left side of the framework and carry a 55 sprocket 311 without the intervening shafts 310 and belts 309.

In order to steady the pin receiver sleeves 295, each one of the sleeves bears against a roller 313 carried by short transverse frame members 314 and positioned diametrically opposite and approximately at the same level as pinion gears 304.

It is believed clear from the above description 60 that the various pin receivers positioned at the setting positions of the pin are moved upwardly to their pin receiving positions by rotation of the appropriate sprockets 311, each pin receiver being operable independently of the other pin receivers. At the time of installation of the apparatus and, of course, at any time thereafter, the tilt of base plate 283 and of adjusting plates 65

286 may be adjusted by operation of jack screws 284 and 288 so as to properly adjust the vertical position of the pin receivers.

As shown in Figures 1, 3 and 4, one of the rear transverse frame members 53 supports ten pneumatic cylinders 320 positioned in two rows at the extreme rear of the machine. Referring now to Figure 15, it will be seen that each of the cylinders 320 receives air through an inlet port 321 at its lower end, the flow of air being controlled by an electro-magnetically operated valve arrangement diagrammatically shown at 322 and shown in detail in one embodiment in Figure 16. Air is supplied to valve 322 through a conduit 323 connected with a manifold 324 to which are connected all ten of the conduits 323 which lead to the various cylinders 320. Manifold 324 is supplied with compressed air by a reservoir 325 which in turn receives air from a compressor 326 driven by a motor 327.

A piston rod 328 extends from the lower end of each cylinder 320 and is attached at its upper end to a piston 329 and at its lower end to a cable 330 which passes over a roller 331 positioned near the lower end of the rear part of the machine and then extends forwardly on the left side of hopper 60. Cable 330 then terminates and is connected to a chain or link belt 332 which forms a continuation of cable 330. Chain 332 passes about one of the sprockets 311 whence it passes rearwardly again to a connection with another piece of cable 333 which passes about a freely running pulley wheel 334 and is attached to cable 330 at the place where the cable is attached to chain 332.

As shown diagrammatically in Figure 15, rotation of sprocket 311 by cable 330 and chain 332 rotates one of the shafts 310 which in turn rotates a sprocket 304 assisted by a counterweight 307. Rotation of sprocket 304 raises the associated pin receiver sleeve 295 to the elevated pin-receiving position.

Near the upper end of each cylinder 320 as shown in Figure 15 is an air outlet port 337 which is connected by means of an appropriate conduit 338 to a female connection box 339 shown in detail in Figures 17 and 18. Connection box 339 cooperates with a male connection box 340 which is connected by means of an appropriate conduit 341 with the appropriate cylinder 190. Cylinder 190 is operable upon receiving air from conduit 341 to pull downwardly cable 199 over roller 200 to open the appropriate sliding door 180 which is positioned over one of the chutes 150 of the movable carriage. This permits a pin to fall from the appropriate compartment 141 of the rotary distributor 140 into the chute 150 therebelow for passage downwardly to the pin receiver 295 aligned therewith and which has been raised by operation of cylinder 320. Because of the position of air outlet 337 near the upper end of cylinder 320, the piston 329 of cylinder 320 must complete a major part of its upward movement and must pass outlet 337 before the compressed air on the under side of piston 329 can pass into outlet 337 to operate cylinder 190. This assures that the pin receiver 295 is in its elevated position before the door 180 is opened to permit a pin to pass downwardly into the pin receiver.

To return now to the electro-magnetically operated valve 322, it will be obvious that various types of standard electrically operable valves may be used. A simplified variation of such a valve is shown in detail in Figure 16 in which one of the transverse frame members 53 in the rear of

the machine is provided with a short upwardly extending support 345 to which is pivoted a horizontal arm 346. The free end of arm 346 is urged upwardly by a coil spring 347 which bears against a fixed platform 348 supported by the framework of the machine in any appropriate manner. Arm 346 also carries a downwardly extending armature 349 which cooperates with a coil 350 in such a manner that the electric energization of coil 350 pulls downwardly on the armature 349 and pivots arm 346 downwardly against the resistance of spring 347. Upon de-energization of coil 350, spring 347 returns arm 346 to its normal position.

A valve supporting tube 351 which may be of the type used with automobile tires is provided with an internal valve 352 of the conventional type which is normally closed and which may be opened by pressure against the lower end 353 of a valve stem 354. Tube 351 is connected by means of a flexible conduit 355 with the conduit 323 leading from manifold 324. Tube 351 extends in a downward direction transversely of arm 346 to which it is attached and at its open lower end cooperates with the upturned end 356 of a tube 357 which is connected to air inlet port 321 of cylinder 320. The upper end 356 of tube 357 carries an upwardly extending projection 358 which cooperates with the lower end 353 of valve stem 354 in such a manner that when coil 350 is energized to pull downwardly on arm 346, tube 351 is moved downwardly to bring the lower end 353 of valve stem 354 into contact with projection 358 causing opening of valve 352 and passage of air from tube 351 into tube 357. Appropriate gasket means (not shown) are, of course, provided to prevent leakage of air after valve 352 is opened.

In order to bleed the air from tube 357 when coil 350 is de-energized, it may be convenient, although not absolutely necessary, to provide a valve 360 in an upwardly directed branch 361 of tube 357 and so arranged as to be normally open when arm 346 is in its normal position and to be closed to prevent exit of air when arm 346 is depressed by energization of coil 350.

Connection boxes 339 and 340 will now be described in detail.

Connection box 339 is fastened to one of the transverse frame members at the rear of the machine in longitudinal alignment with connection box 340 which is carried by the under side of upper movable carriage member 143 near its left edge as viewed in Figure 4 and with the rear surface 365 of box 340 approximately flush with the rear edge of movable carriage member 143.

Box member 340 has ten fore and aft extending bores 366 of slightly diminished diameter at 367 at their rear ends adjacent the rear surface 365 of box 340. The bores or passages 366 are arranged in two rows of five positioned one row above the other and each bore 366 has an inwardly extending annular shoulder 368 in its forward portion. The projection 368 is shown integral with the box 340 in Figure 18. However, in practice this projection 368 may be in the form of a threaded washer which screws into position in an interiorly threaded forward portion of bore 366.

Mounted in each of the bores 366 is a male connector member 370 having its main portion of a diameter only slightly smaller than the diameter of the reduced rear portion 367 of bore 366 and tapered at its rear or outwardly extending end at 371. At its forward end, connector 370 threadedly receives conduit 341 at 372,

Each connector 370 is provided with an annular collar 373 which extends outwardly from its outer surface. The collar 373 may be formed integral with connector 370 or may be threadedly positioned thereon. A coil spring 374 is positioned about connector 370 abutting against projection 368 on box 340 at one end and against collar 373 at its other end so as to tend to maintain connector 370 in its extended position as shown in Figure 18. The provision of springs 374 provides a resilient mounting for the connectors 370 and permits the connectors to be moved a short distance forwardly relative to supporting box 340.

The female connector box 339 which is stationary and fixed to one of the rear transverse frame members of the machine comprises a block having ten fore and aft extending openings 376 positioned similarly to the positions of bores 366 in box 340 and threaded at their rear ends to receive conduits 338. Openings 376 are flared slightly at 378 at their forward ends and are provided with appropriate resilient gaskets 379. The configuration of the flared forward ends 378 of openings 376 is such as to receive the tapered rear ends 371 of male connectors 370 when boxes 339 and 340 are brought together, the male connectors 370 moving into position abutting gaskets 379 so as to provide a sealed connection between conduits 338 and conduits 341, the springs 374 permitting male connectors 370 to give slightly as the boxes 339 and 340 move together.

In order to insure that the boxes 339 and 340 come together in correct alignment, box 339 is provided at each end with a forwardly extending knife-like projection 339a which cooperates with similarly positioned grooves 340a positioned in each end of box 340.

It will be apparent that since connector box 340 is connected to the movable carriage and moves therewith while box 339 is stationary and aligned with box 340, movement of the carriage 145 to its rear position brings boxes 339 and 340 together providing a closed connection by which compressed air can pass through conduits 341 carried in any appropriate manner on the under side of upper carriage member 143 for passage to cylinders 190 which operate sliding doors 180.

When the movable carriage moves away from its rearward position toward its forward position, the connection between boxes 339 and 340 is broken, permitting the air in cylinders 190 to escape and permitting springs 187 to close any of the doors 180 which have been opened.

The electrical control system

Reference is now made to Figures 30 through 36 wherein are shown various features of the electrical control system of the device. In Figure 30 there is shown a wiring diagram in which current is supplied by conductors 400 to a master switch 401. Master switch 401 may conveniently be located in any central control position such as in the manager's office and controls all of the electrical equipment comprising part of the device.

The two poles of switch 401 are connected to alley lights 403 which are controlled by switch 404 operated at control panel 406 (Figure 36) to be referred to in more detail presently. In this manner alley lights 403 may be turned on and off by operation of switch 404.

Also connected across switch 401 is motor 110 which, as described previously, furnishes motive

power for the conveyor system as shown schematically in Figure 24. As shown in Figure 30, motor 110 is under the control of switch 405 which, together with switch 404 is controlled at a control board 406 shown in Figure 36 and positioned conveniently at the bowler's end of the alley for operation by those using the alley. As shown in Figure 36, both of the switches 404 and 405 are controlled by a single switch operator 407, it being, of course, obvious, that both of the switches 404 and 405 may appear on control panel 406, if preferred.

Also deriving power from switch 401 are motor 213 which rotates shaft 214 (see Figure 7) and operates the various mechanisms driven by shaft 214, and ten solenoid controlled valves shown at 322 in Figure 15. As shown in Figure 30 there are ten solenoids 350 for controlling the ten valves. The remainder of the controlling circuit for solenoids 350 will be described presently.

Switch 401 also provides a master control for reversible electrical motor 177 which provides motive power for moving the carriage 145 between its forward and rearward positions, a hand-operated switch 408 being provided on operating panel 406 (Figure 36) for operating motor 177 in either of its two directions of rotation, depending upon the position of switch 408. As indicated in Figure 30, when switch 408 is closed in the direction of the letter R, that is, moved to the "up" position in Figure 36, motor 177 is rotated to move the carriage rearwardly, and when switch 408 is closed in the direction F in Figure 30 (down in Figure 36), motor 177 is rotated in the opposite direction and causes the carriage to move forwardly.

The operation of solenoids 350 is by means of ten individual pin switches 411 positioned on control panel 406 in the same configuration as the pins which they control and numbered accordingly. That is, the number one pin would be controlled by the lowermost switch in Figure 36, that is, the switch beside which the number "1" appears, pins 2 and 3 would be controlled by the two switches in the next row above the No. 1 switch, etc. Switches 411 each control only one of the solenoids 350 and by means of these switches, the bowler may set any selected number of pins simply by closing the appropriate switches 411.

It is obvious that a single switch controlling all of the solenoids 350 may be provided for setting all ten pins without operating all ten of the switches 411. Such a switching arrangement will be obvious to anyone skilled in the electrical art.

Because of the fact that one or more of the switches 411 may be closed by the bowler before the carriage 145 reaches its rearmost or pin-setting position, it is necessary to provide means for assuring that the solenoids 350 will not be energized with the resultant opening of doors 180 and the resultant dropping of pins before the carriage is in the proper position in alignment with the pin receivers in the floor. For this purpose, the switch 412 shown in detail in Figure 33 is mounted on the inside of one of the longitudinal frame members 51 on a bracket 413 mounted on a pivot 414. Bracket 413 extends downwardly and carries a small counterweight 415 at its lower end which tends to balance partly the mercury in switch 412, but nevertheless permits switch 412 to remain normally in its open position. The forward and lower portion of bracket 413 is adapted to be engaged by a projection 416

extending upwardly from the travelling carriage so that when the carriage reaches its rearward position, projection 416 engages the downwardly extending portion of bracket 413 to pivot the bracket and switch 412 about the pivot point 414. This closes switch 412 and permits energization of one or more of the solenoids 358 by means of switches 411. When the carriage moves forwardly again, the weight of the mercury in switch 412 causes the switch to move in a counterclockwise direction as shown in Figure 33 until the rear end portion of bracket 413 strikes a detent 418 which defines the normal position of the switch. In this position the switch 412 is tilted with its rear end slightly below its forward end so that the mercury moves away from the two contacts of the switch and opens the circuit, thus disabling the solenoid operating circuit.

The motor 213 which has been described previously is controlled by a switch 420 in addition to switch 401. Switch 420 is of the mercury type having a pair of contacts 424 in its rear end and a pair of contacts 425 in its front end, the switch being shown in detail in Figure 34. As shown in that figure, switch 420 is mounted on a curved arm 421 which is movable about a pivot 422 in a manner similar to the mounting of switch 412. Pivot 422 extends transversely from the inner side of one of the longitudinal frame members 51 so that the downwardly extending rear end of arm 421 extends into the path of an upwardly extending projection 423 mounted on the upper surface of the upper member 143 of the movable carriage. When the carriage moves to the extreme forward position, projection 423 tips arm 421 and thereby switch 420 so as to lower the rear end of the switch capsule and permit the mercury in the switch to close the rear pair of contacts 424 of the switch. The closing of contacts 424 sets motor 213 into operation, thereby initiating the operation of the several movable parts mounted on the bridge-like framework which are driven by motor 213.

When the movable carriage moves rearwardly away from its forward position, the weight of the switch 420 tips the switch to the position shown in Figure 34 so that the forward end of the switch capsule is lower than the rear end. The mercury in the switch runs to the lower end and opens contacts 424 and closes contacts 425 located in the forward end of the switch capsule. It will be clear from the above description that contacts 424 remain open and contacts 425 remain closed during that portion of the operation of the machine in which the movable carriage is not in its extreme forward position. The condition of switch contacts 424 and 425 is reversed when the movable carriage is in its extreme forward position, that is, a circuit which includes contacts 424 is closed while that which includes contacts 425 is open. The function of contacts 425 in the operation of the machine will be explained in detail presently.

The control of reversible motor 177 includes several elements of novel construction. Motor 177 is of the reversible type and has a ground lead 430 attached to one pole of switch 401 while the switch 408 previously described takes part in the control of the direction of motor 177 by controlling whether current flows through a lead 431 which causes motor 177 to move the carriage rearwardly or whether the current passes to lead 432 which causes the carriage to move forwardly. Other control devices which assist in the control of motor 177 will now be described.

As shown in Figure 35, each of the pin receivers 295, 296 is provided with a mercury switch 435 mounted so as to be closed when its pin receiver is completely lowered. This mounting includes bracket 436 carried by one of the transverse members 314 and having at its upper end a pivotal mounting 437 for a switch capsule support 438. One end of support 438 extends toward the pin receiver and is adapted to be engaged by the lower end of sleeve 296 which is attached to sleeve 295 of the pin receiver as has been described previously. Switch capsule 435 is positioned slightly off center with respect to pivot 437 and a small counterweight 440 is provided on the support 438 to cause the support to pivot in a clockwise direction as viewed in Figure 35 when the pin receiver sleeve 296 is elevated. Counterweight 440 is positioned so as to contact bracket 436 to define the limit of clockwise movement of support 438. This assures that support 438 will remain in position to be engaged by the lower end of pin receiver sleeve 296 when the pin receiver is lowered.

As shown in Figure 35 each switch 435 is closed when its pin receiver sleeve 296 is in the lowered position. Switches 435 are connected in series in the circuit which causes motor 177 to move the carriage forwardly. As long as any one of the switches 435 is open, indicating that one of the pin receivers is still raised, the circuit which causes operation of motor 177 to move the carriage forwardly is broken.

Also included in series with the pin receiver switches 435 is a safety switch 441 mounted on the main framework of the machine in its extreme forward end. Switch 441 is normally closed and is opened when the upper member 143 of the carriage strikes the plunger of the switch. Switch 441 is not normally operated but serves as a safety switch which automatically breaks the circuit energizing motor 177 for forward movement of the carriage in case maladjustment of the mechanism for operating switches 490-491 (to be discussed presently) permits the motor to move the carriage past its forward or magazine loading position.

A similar safety switch 444 shown in Figure 33 is positioned on the main framework of the machine so as to be engaged by the carriage in case it passes the extreme rearward position. If this occurs, the carriage actuates plunger 445 of switch 444 to open the switch and thereby break the circuit which operates motor 177 to move the carriage rearwardly.

Also included in the circuit which operates motor 177 to move the carriage rearwardly is a switch 446 which is of the mercury type and which is mounted as shown in Figures 5 and 7 on an upwardly extending bracket 447 carried by one of the transverse members 211 of the bridge-like framework shown in Figure 5. The switch capsule is mounted near one end of a straight supporting arm 448 which is pivotally carried by the upper end of bracket 447. The other end of arm 448 extends above shaft 214 so as to be engaged by a short cam arm 449 which is mounted on shaft 214 and extends transversely thereof. The contacts of switch 446 are located at the end of the switch capsule removed from shaft 214 and switch supporting arm 448 is balanced so as to be heavier on the end which cooperates with shaft 214 and cam 449. When cam 449 contacts switch capsule support 448 the capsule is tilted to the position shown in Figure 5 in which the end of the capsule in which the contacts are located is lower than the other end, causing the

mercury to close the circuit which includes the contacts. When shaft 214 rotates cam arm 449 out of contact with capsule support 448, the switch capsule tilts so that the mercury runs away from the switch contacts and breaks the circuit.

Cam arm 449 is positioned on shaft 214 so that it engages switch support 448 at a time when the rotatable drum 140 is stationary and doors 250 are closed. It is only when this condition prevails that it is desired that the movable carriage move rearwardly out from under the bridge-like framework. Inasmuch as switch 446 is connected in series in the circuit which controls operation of motor 177 to cause rearward movement of the carriage, such rearward movement cannot take place when switch 446 is open. As pointed out above, switch 446 is closed only when the movable parts mounted on the bridge-like framework and the rotatable drum 140 are in the desired condition.

Since it would be possible even after motor 177 has been energized and motor 213 de-energized for the inertia of the mechanism to carry cam arm 449 past the position in which it causes switch 446 to close, provision must be made to assure that the circuit of motor 177 will not be broken in case such condition prevails. The means provided for assuring the continuance of operation of motor 177 to drive the carriage rearwardly once this rearward motion has begun, comprises contacts 425 of switch 420 shown in Figure 34 and previously described. It will be recalled that when the carriage is in its extreme forward position contacts 425 are open and that as soon as the carriage moves a short distance away from its forward position switch 420 tilts so as to close contacts 425. As shown in Figure 30, contacts 425 are connected in parallel with switch 446, so that a slight movement of the carriage rearwardly causes closing of contacts 425 and assures that motor 177 will continue in operation regardless of any inertia actuated movement of cam arm 449 which might permit switch 446 to reopen.

In order to provide the necessary reversal of polarity to operate the type of reversible motor used in the embodiment of the machine illustrated, there is provided the apparatus shown in Figure 31 which shows diagrammatically most of the circuit used purely for control of motor 177. The circuit connections are also shown, of course, in Figure 30.

Referring now to Figure 32 there is seen motor 177 which through pulley arrangement 176 drives a sprocket 174 which is keyed to a transverse shaft 173 which is provided at its ends with sprockets 172 over which pass the two endless link belts 170 which move the carriage forwardly and rearwardly. On one end of shaft 173 is another sprocket 460 which drives another sprocket 461 by a short length of endless link belt 462. Sprocket 461 is keyed to a short transverse shaft 463 which is journaled at 464 and 465 to the front surface of a panel 466 mounted in a vertical position facing forwardly on the framework at the rear of the machine. The central portion 467 of shaft 463 comprises a worm gear along which runs an internally threaded nut 468.

Nut 468 is flat sided at the rear and bottom which cooperate respectively with the front surface of panel 466 and with a forwardly extending shelf 469 positioned a short distance below shaft 463 and extending parallel therewith. This cooperation of the rear and bottom surfaces re-

spectively with the front of panel 466 and with the upper side of shelf 469 prevents rotation of nut 468 and causes the nut to move longitudinally with respect to worm gear 467 as shaft 463 is rotated. The direction in which nut 468 will travel upon rotation of shaft 463 depends upon the direction of rotation of the shaft.

Nut 468 has two upward extending portions 470 at its ends which provide mountings for adjusting screws 471 which extend into the gap between the two arms 470.

Approximately midway between the ends of the worm 467 and spaced thereabove on panel 466 is a forwardly extending pivot shaft 474. Rotatably mounted on pivot 474 are two downwardly extending members. The first of these members is mounted nearest the surface of panel 466 and comprises an arm 475 which extends downwardly to a point between upwardly projecting arms 470 of nut 468. A coil spring 476 is attached at a central point 477 on the upper portion of panel 466 and is also attached at 478 to the lower end of arm 475. Spring 476, because of its central anchorage at 477, tends to move arm 475 in a clockwise direction when the lower end of arm 475 is to the left of pivot 474, and tends to move arm 475 in a counterclockwise direction when the lower end of arm 475 is to the right of the pivot 474. The latter condition prevails in Figure 32.

Near the upper end of arm 475 are two forwardly extending and transversely spaced ears 480 through which pass transversely extending adjusting screws 481 which extend into the gap between the two ears 480 and between the two adjusting screws 481 extends an arm 483 which comprises the second of the two members which are pivotally mounted upon pivot 474.

Arm 483 is carried by a hub 484 to the upper part of which is fixed a rectangular plate 485 extending at right angles to arm 483.

A second coil spring 486 is fixed at point 477 to panel 466 and is attached at 487 to the lower end of arm 483. Spring 486 serves the same function with respect to arm 483 as does spring 476 with respect to arm 475, and tends to maintain arm 483 against one or the other of the two adjusting screws 481 depending upon whether arm 483 is to the left or right of the center line of panel 466.

Plate 485 which rotates about pivot 474 with arm 483 carries six mercury switches mounted in two groups of three each, one group 490 being positioned near one end of plate 485 and the other set of three switches 491 being positioned near the other end of plate 485. The switches of groups 490 and 491 are positioned with their capsules extending parallel to each other and parallel to the surface of panel 466. The contacts of each switch are positioned in the direction of the end of plate 485 nearest that switch, that is the contacts of the switches of group 490 are adjacent the right end of plate 485 as viewed in Figure 32, while the contacts of the switches of group 491 are positioned adjacent the left end of plate 485. Panel 466 is provided with appropriate terminal posts 493 for the attachment of the leads from switches 490 and with terminal posts 494 for the attachment of leads from the switches 491.

From the drawings and the above description, it will be apparent that with the carriage in its forward position, operation of motor 177 to move the carriage rearwardly also causes rotation of shaft 463 which causes movement of nut 468 along the worm gear portion 467 of the shaft. By correctly proportioning the gear ratios and by cor-

rectly adjusting the screws 471 and 481, plate 485 will be arranged to tilt so as to operate switches 490 and 491 to open one set of switches and close the other set of switches when the carriage reaches its rear position, thus breaking the circuit which operates motor 177 to drive the carriage rearwardly and closing those of the switches 490 and 491 which prepare the controlling circuit for causing motor 177 to move the carriage forwardly when the other elements of the controlling circuit are operated.

When switch 408 is then moved to cause forward motion of the carriage, motor 177 drives the carriage forwardly until rotation of shaft 433 and worm gear 467 moves nut 468 to the opposite end of the worm gear causing tilting of plate 485 to close those of switches 490 and 491 which have been opened and to open those which have been closed. This, of course, breaks the circuit to motor 177 which causes forward motion of the carriage and prepares the circuit which causes rearward motion for operation when the remainder of the circuit is operated correctly to so move the carriage.

The provision of safety switches 441 and 444, as previously explained, prevents damage to the mechanism in case maladjustment of the control circuit for motor 177 fails to stop the motor at either end of the travel of the carriage.

In connection with the control circuit for motor 177 it should be pointed out that the four leads, A, B, C, D, coming out of motor 177 in Figure 30 and connected to switches 490 and 491 have been shown in Figure 30 as comprising a single connection for most of the distance between motor 177 and switches 490 and 491. This showing is merely for convenience and to add to the clarity of the circuit diagram. Actually, of course, the connections, A, B, C, D, are separate and are connected as shown by the letters which designate each lead. It will also be clear that each lead A, B, C, D has two branches, one of which connects to a switch of group 491 while the other connects to a switch of group 490. When switches 491 are closed it will be clear that leads A and B are connected and leads C and D are connected. When switches 490 are closed, leads A and D are connected and leads B and C are connected, thus reversing the polarity of the field coils of motor 177 and causing the motor to rotate in the opposite direction.

Figure 38 shows a modified operating circuit for motor 177a utilizing a simple type of reversing motor. This circuit merely utilizes switches 444a and 444a to stop the motor 177a when the carriage reaches its forward or magazine loading position and its rear or pin setting position. Other types of circuits may be obvious to those skilled in the art.

The sweep

Due to the fact that it is necessary during use of the pin setting apparatus to remove "dead wood" and standing pins from the alley, a sweep operated by the moving carriage has been provided. The sweep comprises a sheet of canvas 500 having a width approximately equal to the width of the alley. At its lower end the sweep is attached to a weighted bar 502 which, as shown in Figure 4, is provided at its ends with downwardly extending portions complementary to the contour of the grooves 501 at each side of the alley. The upper end of the canvas part of the sweep 500 is attached at 504 to the rear edge portion of the lower carriage member 146.

The central portion of the canvas 500 passes over a roller 505 rotatably mounted in a movable roller support 506. Roller support 506 is slidably mounted for forward and rearward movement along a pair of inwardly facing angle irons 507 disposed one on each side of the alley and suspended below main longitudinal frame members 51 by means of downwardly extending members 508. Supports 507 are positioned at such a height above the alley as to be approximately level with the lower member 146 of the carriage. As the carriage moves rearwardly from its forward position the rear edge of lower carriage member 146 engages the roller support 506 and pushes the support rearwardly until the roller support 506 reaches its extreme rearward position as shown in Figure 2 in which the weighted cross bar 502 of the sweep is suspended closely adjacent the surface of the alley at the forward edge of hopper 60. It will be apparent from Figures 1 and 2 that during the portion of the rearward movement of the movable carriage which precedes contact of the carriage with roller support 506, the canvas 500 is running loosely over roller 505 so that bar 502 moves downwardly pulling the canvas sweep 500 with it. As soon as the carriage engages roller support 506 and moves the support rearwardly before the carriage, the sweep 500 and the weighted bar 502, of course, move rearwardly along the surface of the alley upon which the pins are set and along the adjacent portions of grooves 501, sweeping the alley and the grooves clean of pins and balls and pushing the same rearwardly into hopper 60 whence they pass to the lower end of subconveyor 63 in the manner shown in Figure 25. In order to avoid jams in hopper 60 it may be desirable to cause a part of the bottom of the hopper to vibrate by a motor and cam or other suitable means (not shown).

Spaced slightly above and parallel to guides 507 are a pair of retainer bars 510 (Fig. 10). Retainer bars 510 are supported by means of metal brackets 511 which extend upwardly along the outer surfaces of members 507 and then extend inwardly a short distance at 512. The horizontal portions 512 of members 511 are provided with vertically extending rods 513 which are fixed at their lower ends in retainer bars 510 and at their upper ends slidably pass through suitable openings in horizontal portions 512 of members 511. The extreme upper ends of rods 513 are threaded and are provided with suitable nuts 514 which are adjustable to limit the extent of downward movement of rods 513 and members 510. Helical springs 515 surround the portions of rods 513 which lie between the upper surfaces of members 510 and the horizontally extending portions 512 of members 511 so as to urge retainer bars 510 downwardly at their forward and rear ends.

Retainer bars 510 are beveled on their forward under surfaces at 517 and are positioned at such a height that in their lowermost positions their under surfaces lie slightly below the upper surface of roller support 506.

When roller support 506 is moved rearwardly by the movable carriage, the roller support moves freely until it engages beveled portions 517 of retainer bars 510 at which time the roller support 506 moves underneath the retainer bars 510 forcing the bars upwardly slightly against the tension of springs 515. The tension of springs 515 is not sufficient to prevent continued rearward movement of roller support 506 and the

support continues its rearward movement to the position shown in Figure 2.

When the carriage is moved forwardly from its rearward position as shown in Figure 2, retainer bars 510, because of their frictional engagement with roller support 506, retain the roller support in its extreme rearward position permitting the forward movement of the carriage to pull canvas 500 upwardly over roller 505 carrying with it the sweep bar 502. Thus the sweep bar and canvas 500 move upwardly to a position in which they will clear the newly set pins on the alley and as soon as bar 502 comes against roller support 506 through which it is unable to pass, the pull exerted on canvas 500 by the forwardly moving carriage begins moving roller support 506 forwardly from its extreme rearward position despite its frictional engagement with retainer bars 510. The forward movement of roller support 506 continues until the carriage reaches its extreme forward position at which time the roller support has moved well clear of retainer bars 510 to a position substantially forward of the No. 1 pin where it is again ready to be lowered by rearward movement of the carriage to sweep the alley.

The safety bar

In order to protect the mechanism against damage by the intentional or unintentional rolling of a ball down the alley during the time that the pin receivers are raised and the pin setting function is in process, a safety bar 520 has been provided which will be lowered to a blocking position resting on the alley surface well forward of the No. 1 pin during the time that pins are being set. Bar 520 consists of any suitable substantial member of sufficient mass to stop a ball rolling down the alley. The bar is attached to a pair of ropes or cables 521 which are attached at their forward ends to eyes 522 attached to the under side of lower carriage member 146 near its two forward corners. Cables 521 run over front and rear sets of rollers 523 attached to the forward end portions of guide members 507 so that rearward movement of the carriage will permit gravity to move the bar 520 downwardly until it rests upon the alley surface. As long as eyes 522 are forward of rollers 523, cables 521 run over the forward set of rollers. The rear set of rollers 523 carry the cables 521 when eyes 522 are to the rear of the rollers. A pair of springs may be provided to pull cables 521 upwardly out of the way during the central portion of the travel of the carriage when there is considerable slack in the cables 521. As shown in Figure 2, the cables 521 are of sufficient length that the bar 520 remains in its position on the alley surface during the rearward portion of the travel of the carriage.

It will be apparent that upon forward movement of the carriage the bar 520 will be hoisted to its normal position as shown in Figure 1 by the pull exerted upon cables 521 by the carriage.

Overall operation

In order to make the operation of the mechanism more easily understood it will be helpful to run through a cycle of the operation of the machine, beginning with the carriage in its forward position.

When the manager of the establishment using the machine desires to place the alley in readiness for use by customers he closes switch 401.

When the customer is ready to begin using the alley he closes switches 404 and 405 by moving switch operator 407 located on the panel 406 at the forward end of the alley, thereby turning on the alley lights 403 which are located at an appropriate place for illuminating the rear end of the alley and turning on conveyor motor 110 to set the conveyor system into operation (Figure 24).

The operation of conveyor motor 110 causes any pins which have remained in the hopper 60 or in the conveyors themselves to be carried to the upper end of the main conveyor and deposited in chute 118 where they pass downwardly toward rotary conveyor 140. Two or preferably three full sets of pins are used with the machine so that when the pin receiving openings 141 in rotary conveyor 140 are all full the remaining pins can be stored end-to-end in chute 118. If there are ten pins on the alley in set position and ten pins in the openings 141 of the rotary conveyor, there will be ten pins distributed in one place or another in the hopper 60, in the conveyor system or in the chute 118.

Since the carriage is in its forward position, the upwardly projecting block 423 on the carriage retains switch 420 in a position so as to close contacts 424 (Figure 34) and motor 213 located on the bridge-like supporting framework begins running upon the closing of master switch 401.

The rotation of motor 213 drives shaft 214 (Figure 7) and thereby operates the slide bar 218 which indexes the rotary distributor 140 by means of pivoted arm 221 engaging projections 232 on the rotary conveyor. Rotation of shaft 214 also rotates cam 263 (Figures 7 to 9) which causes oscillation of arcuate member 276 mounted over the center of the lower end of chute 118 in a position to engage the pins as they pass downwardly in the chute.

Reciprocating doors 250 are also operated by rotation of shaft 214 and function to permit only one pin to pass into each of the openings 141 in the rotary distributor and, by cam-like action of their curved inner ends 255 acting against the tapering base of a pin which may have passed part way through the doors and then encountered another pin already in the opening 141 therebelow, to push the upper pin upwardly clear of the rotary distributor where the pin remains during indexing of the rotary distributor to bring the next opening 141 below doors 250. If the next opening 141 contains a pin, the doors 250, after permitting a pin to pass partly therethrough will again push the pin back up above doors 250 and close until the next indexing movement of the rotary distributor is completed. This will continue until an empty opening 141 comes beneath the opening between doors 250 at which time the opening of the doors permits a pin to drop into the opening 141. The function of the oscillating arcuate arm 276 is to take the weight of the column of pins in chute 118 off of doors 250 and to assure that only one pin at a time will be resting upon these doors.

As long as switch 401 is closed and the carriage is in its extreme forward position motor 213 will continue its rotation and the function of the various parts operated by motor 213 will continue. This will fill all of the pin receiving openings 141 in the rotary distributor and after all of these openings are full the various operations performed by the mechanism driven by

motor 213 will continue as has been previously described.

Now the bowler is ready to begin the game and rolls a ball down the alley toward the ten pins which we will assume were already set. If the ball knocks down say eight of the pins and there is no "dead wood" left on the alley which needs to be removed, the bowler may proceed with the next ball. However, if there is "dead wood" which must be removed, the bowler notes which of the pins were left standing; let us assume pins 6 and 9 remain. He then moves switch 409 upwardly as viewed in Figure 36 to the position designated for moving the carriage to the rear.

With switch 408 in the position to move the carriage to the rear, and as so on as rotation of shaft 214 brings the cam arm 449 (Figure 5) to a position to tip member 448 and close switch 446, the circuit which drives motor 177 in the direction to cause rearward movement of the carriage is completed and the carriage begins its rearward movement. As soon as the carriage has moved rearwardly a short distance, switch 420 (Figure 34) is tilted to open contacts 424 and de-energize motor 213. Tilting of switch 420 closes contacts 425 to by-pass switch 446 (Figure 5) so that motor 177 will remain in operation even though the inertia of the mechanism carries shaft 214 and cam arm 449 past the position in which they close switch 446.

As the carriage moves rearwardly toward the position shown in Figure 2 it causes the lowering of sweep 500, 502 followed by rearward movement of the sweep to clear the alley and adjacent sections of grooves 501 of "dead wood," standing pins, and balls. Rearward movement of the carriage also lowers safety bar 520 to the surface of the alley between the bowler and the set position of the pins.

When shaft 473 has made the correct number of revolutions to move the carriage to its rearward or pin setting position, the mechanism shown in Figure 32 turns off motor 177 by operating switches 490 and 491 and at the same time prepares motor 177 for operation in the opposite direction at the proper time.

Movement of the carriage to its rearward position also closes switch 412 (Figure 33) which readies solenoids 350 and thereby the pin receivers 295, 296 located beneath the surface of the alley for operation.

When the bowler sees that the carriage has reached its extreme rear position he closes those switches 411 on the panel which are in the same positions relative to each other as pins 6 and 9 which he desires to reset. These switches will be designated on the panel by the numbers 6 and 9 for his convenience. The closing of these switches energizes those of solenoids 350 which operate the appropriate valves 322 to admit compressed air to the lower ends of the two appropriate cylinders 320 located at the rear of the machine. It will be recalled that switch 412 was closed when the carriage reached its rearmost position. The operation of the two appropriate cylinders 320 causes upward movement of their pistons 329 pulling on their cables 330 which rotate the two appropriate sprockets 341 and raise the pin receivers 295, 296 located in the No. 6 and No. 9 positions (see Figure 15).

As the pistons 329 approach the upper end of their path of movement and the pin receivers 295, 296 controlled thereby are also approaching the limit of their upward movement, the pistons pass ports 337 located near the upper ends of

cylinders 320 and permit the air which has been moving the pistons upwardly to pass through ports 337 and into conduits 338 which connect with connector box 339. Connector boxes 339 and 340, of course, have been brought together by movement of the carriage and the connector box carried thereby to the extreme rear position. With connector boxes 339 and 340 in engagement, each of the conduits 338 is connected to the matching conduit 341 and when air passes into conduits 338 it then passes through the connected conduits 341 and operates the two cylinders 190 which open the two doors 180 located over the two chutes 150 which terminate at their lower ends above the No. 6 and No. 9 pin positions. The opening of the appropriate doors 180 permits the two pins thereabove in rotary distributor 140 to pass downwardly through their chutes 150 into the two pin receivers which have been elevated to the pin receiving position above the alley surface.

As long as one or more of the pin receivers 295, 296 is elevated, the opening of the corresponding switches 435 (Figure 35) assures that motor 177 cannot be operated to move the carriage away from the rear position.

As soon as the proper pins have been dropped into the two pin receivers the bowler returns the switches 411 for pins No. 6 and No. 9 to their "off" positions thereby de-energizing the two solenoids controlled by these two switches. The de-energization of the two solenoids 350 permits springs 347 (Figure 16) to move arm 346 permitting valve 352 to close and permitting valve 360 to open. This shuts off the flow of compressed air and vents the air in the lower part of cylinder 320 through valve 360 permitting the piston 329 to return to its normal lowered position as shown in Figure 15.

As soon as the weight of two pin receivers 295, 296 causes them to return to their lowered positions, they again close the two switches 435 associated therewith (Figure 35) and place the motor 177 in condition for operation to move the carriage forwardly.

When the two pin receivers reach their lowered positions, the bowler moves switch 408 to the lower position as viewed in Figure 36 to cause forward movement of the carriage. As all ten of the switches 435 are closed, safety switch 441 is closed, and the switches 490 and 491 have made the appropriate connections within motor 177, the downward movement of switch 408 causes the carriage to begin its forward movement accompanied by raising of sweep bar 502, return of the sweep bar to its forward position, and raising of the safety bar 520. Springs 187 close doors 180.

It should be pointed out that movement of the carriage forwardly from its rearward position opens switch 412 which breaks the circuit to solenoids 350 and thereby renders the solenoids inoperative until return of the carriage to its rearmost position.

When the carriage reaches its forward position it tilts switch 420 breaking contacts 425 in the circuit of motor 177 and closing contacts 424 in the circuit controlling motor 213. The closing of contacts 424 sets motor 213 in operation again and begins the refilling of openings 141 in rotary distributor 140 which have been emptied by the setting of the two pins.

Under normal circumstances the apparatus shown in Figure 32 for tilting switches 490 and 491 causes motor 177 to be de-energized to halt the forward movement of the carriage when the

carriage reaches its forward position; the tilting of switches 490 and 491 also being operable to make the appropriate connections and disconnections of leads A, B, C, D to ready motor 177 for operation in the reverse direction. Safety switch 441, normally in closed position, is placed so as to be opened by movement of the carriage past its forward position, and serves as a safety cut-off for motor 177 in case of mechanical failure or maladjustment in the parts which tilt switches 490 and 491.

It is believed clear that instead of setting two of the pins the bowler could have set any other number of pins by operation of the appropriate switches 411 on panel 401. A simple circuit could be provided as by using separate mercury switches for controlling each solenoid 350 whereby should he desire to reset all ten of the pins at once, the bowler has merely to operate a single switch which is connected to a solenoid which closes all of the mercury switches which energize all ten of the solenoids 350 to cause all ten of the doors 180 to open after all ten of the pin receivers are raised out of the floor to receive ten pins at once.

Resilient positioning of movable carriage

In a refined variation of the apparatus as illustrated in Figure 37 a resilient arrangement is provided for positioning the carriage and the rotary distributor carried thereby in the correct forward position beneath the bridge-like supporting framework 210, 211, assuring the correct position for indexing of the rotary distributor by the mechanism provided for this purpose, and for the reception of pins dropping through the two reciprocating doors 250.

This is done by constructing the bridge-like framework at the forward end of the machine so as to include longitudinal supporting members 608 on each side of the framework each of which rides upon a pair of rollers 601 supported by the longitudinal frame member 51 on that side of the machine. A spring 602 tends to pull the framework rearwardly against a pair of stops 603 on frame members 51.

The movable carriage carries an upwardly extending member 604 on its rear end which is adapted to engage a transverse member of the bridge-like framework when the carriage moves to its forward position and thereby to align the carriage and the parts carried thereby with the bridge-like framework. Member 604 also causes the bridge-like framework to move forward with the carriage, moving the bridge-like framework out of contact with stops 603 and tensioning spring 602.

When the carriage stops moving forwardly, the framework stops with it and remains in alignment due to the spring 602 maintaining the framework in contact with member 604.

When the carriage moves rearwardly, the bridge-like framework moves with it a short distance under the influence of spring 602 until the framework is halted by stops 603, permitting the carriage to continue its rearward movement.

I wish it to be understood that my invention is susceptible of numerous variations without departing from the inventive concept as defined by the appended claims. For example, other electrical control circuits may be provided and minor variations in the mechanical arrangements may be carried out without deviating from my invention. It is also apparent that the invention is applicable to both duck pins and ten pins, the names commonly given the small and large size

pins. I also wish to point out that the specific construction of the supporting framework, both above and below the alley comprises no part of my invention and may be varied to suit the particular installation. Likewise, the shafting arrangement in the supporting framework for the pin receivers 295, 296 may be widely varied without departing from the invention.

For an example of a modified operating circuit for motor 177, reference is made to Figure 38 wherein is shown a simplified circuit. In the wiring diagram of this figure, a simple reversible motor 177a replaces motor 177 and a switch 408a having open circuit, forward and rearward positions, replaces switch 408. The carriage is stopped at its forward and rearward positions by normally closed switches 441a and 444a positioned similarly to switches 441 and 444 at the rear and forward ends of the path of movement of the carriage. When the carriage reaches its rearward or pin setting position it opens switch 444a and breaks the circuit which operates motor 177a in a direction to move the carriage rearwardly. Switch 441a performs a like function to stop forward movement of the carriage when it reaches its forward or magazine loading position.

I claim:

1. A mechanical pin setter for use with a bowling alley, comprising a movable carriage positioned above the rear end of the alley, a pin magazine carried by the carriage, means for moving the carriage and magazine between a magazine loading position and a pin setting position above the set positions of the pins, means operable only when said magazine is in the pin setting position for discharging pins from the magazine, pin receivers positioned in the alley at the set positions of the pins with their upper ends normally flush with the alley surface, means for moving the pin receivers to elevated pin receiving positions, means rendering said pin receiver moving means inoperative in response to movement of said carriage from said pin setting position, means for carrying pins to the loading position of said magazine and carriage, and means preventing movement of pins from the last-mentioned means to said magazine and operable in response to movement of said magazine from said magazine loading position.

2. A mechanical pin setter for use with a bowling alley, comprising a movable carriage positioned above the rear end of the alley, a pin magazine carried by the carriage, means for moving the carriage and magazine between a magazine loading position and a pin setting position above the set positions of the pins, means operable only when said magazine is in the pin setting position for discharging pins from the magazine, pin receivers positioned in the alley at the set positions of the pins with their upper ends normally flush with the alley surface, means for moving the pin receivers to elevated pin receiving positions, means rendering said pin receiver moving means inoperative in response to movement of said carriage from said pin setting position, conveyer means for carrying pins to an elevated position, chute means for guiding pins from said elevated position into loading relationship with said magazine when said magazine is in its loading position, retainer means operable to prevent movement of pins from said chute means, and interlock means maintaining said retainer means in operable position as long as said magazine is in other than its loading position.

3. A mechanical pin setter for use with a

bowling alley, comprising a movable carriage positioned above the rear end of the alley, a rotatable pin magazine carried by said carriage, first power means for moving said carriage and magazine between a magazine loading position and a pin setting position approximately above the set positions of the pins, ten pin receivers positioned in the alley at the respective set positions of the pins, said pin receivers having normal lowered positions in which their upper ends are flush with the surface of the alley and elevated pin receiving positions in which their upper ends receive pins from said magazine when the magazine and carriage are in their pin setting position, second power means for moving said pin receivers to said elevated positions, closure means carried by said carriage normally retaining pins in said magazine and movable to pin releasing positions, third power means for moving said closure means to said pin releasing positions, conveyer and guide means carrying pins to the loading position of said magazine, retainer means controlling passage of pins from said conveyer and guide means to said magazine, said retainer means being movable between a pin movement blocking position and a non-blocking position, fourth power means for moving said retainer means between said positions, remotely operable control means for energizing said first, second, third and fourth power means, and an interlock system controlled by movements of said carriage, said magazine, said pin receivers and said retainer means for energizing said first power means to move said carriage from said magazine loading position toward said pin setting position only when said retainer means are in pin movement blocking position, for energizing said second power means only when said carriage and magazine are in said pin setting position, for energizing said third power means only after said pin receivers have substantially reached their elevated positions, and for energizing said first power means to move said carriage and magazine from said pin setting position toward said magazine loading position only when all of said pin receivers are in their normal positions.

4. A mechanical pin setter as set forth in claim 3 in which said magazine has ten pin receiving openings, said closure means including ten doors, each door normally retaining one pin in said magazine, said third power means comprising ten separate power devices operatively associated one with each of said doors, said remotely operable control means including devices for selectively energizing said power devices to move selected doors to open positions releasing selected pins for downward movement to said pin receivers, said second power means including ten separate power devices operatively associated one with each of said pin receivers, said remotely operable control means including devices for selectively energizing said pin receiver elevating power devices, said interlock system including means interconnecting each of said door operating power devices with the corresponding pin receiver operating power device to cause operation of the door operating power device only after operation of the associated pin receiver operating power device, whereby the selected pin receiver substantially reaches its elevated position prior to opening of the associated door to release a pin for downward movement to the pin receiver.

5. A mechanical pin setter as set forth in

claim 4 in which said door operating power devices and said pin receiver operating power devices comprise fluid pressure operable piston and cylinder means, means for supplying fluid pressure to each of said pin receiver operating piston and cylinder means, said interconnecting means including a fluid conduit connecting each of said pin receiver operating piston and cylinder means with the corresponding door operating piston and cylinder means in such manner as to feed fluid pressure to said door operating piston and cylinder means only after the corresponding pin receiver operating piston and cylinder means has substantially completed its pin receiver elevating stroke.

6. A mechanical pin setter as set forth in claim 3 in which said first power means includes a reversible electric motor, operating circuits for energizing said motor in each direction of rotation, means operably connecting said motor and said carriage so that rotation of said motor in a first direction moves said carriage from said magazine loading position to said pin setting position while rotation of the motor in a second and opposite direction moves the carriage from the pin setting position to the magazine loading position, and switch means in said circuits for automatically deenergizing said motor when said carriage reaches either of said positions.

7. A mechanical pin setter for use with a bowling alley, comprising a movable carriage positioned above the rear end of the alley, a rotatable pin magazine having ten circularly disposed pin receiving openings and mounted on said carriage, said carriage having a magazine loading position and a pin setting position, guide means on said carriage for guiding pins from their circular relative disposition to the conventional relative disposition of the set pins, said guide means having upper end openings circularly disposed and alignable with the ten openings in the magazine, ten sliding doors mounted on said carriage one above each of said upper end openings and normally retaining pins in said magazine against passage downwardly into said guide means, ten fluid pressure operated piston devices operably connected one to each of said doors for moving said doors to open pin releasing positions, ten pin receivers positioned in the alley at the ten set positions of the pins and having normal lowered positions flush with the alley surface and elevated pin receiving positions, each pin receiver having a pin receiving opening in its upper end and a flat surfaced member movable in the opening and forming a bottom for the opening and a resting surface for a pin received by the pin receiver when the receiver is in its elevated pin receiving position, means cooperating with said pin receiver for positioning said flat surfaced member with its upper surface flush with the alley surface when the pin receiver is in its normal position, a second group of ten fluid operated piston devices operatively connected one with each of said pin receivers for elevating said pin receivers, fluid pressure supply means for said second group of piston devices, ten selectively and remotely controllable valve means disposed one in the supply means for each piston device of said second group, a conduit connecting each piston device of said second group with the piston device which operates the door closing the guide means leading to the pin receiver which that piston device of the second group operates, said conduits being connected to the piston devices of the second group in such a manner as to carry operating

fluid pressure to the corresponding door operating piston devices only when said devices of the second group have substantially completed their pin receiver elevating strokes, reversible electric motor means for moving said carriage and magazine from said magazine loading position to said pin setting position on rotation in a first direction and for moving said carriage from said pin setting position to said magazine loading position on rotation in a second and opposite direction, first and second operating circuits connected to said motor means for operating said motor means in each of said first and second directions, respectively, switch means in said first circuit operable to deenergize said first circuit when said carriage reaches said pin setting position, switch means in said second circuit operable to deenergize said second circuit when said carriage reaches said magazine loading position, pin receiver operated switch means in said second circuit for rendering said second circuit inoperative when one or more of said pin receivers is in other than its normal position, conveyer means receiving pins and balls at the rear of the alley and raising pins to an elevated position, means in said conveyer means for properly orienting said pins, means cooperating with said conveyer means for separating the balls from the pins, chute means guiding pins from said elevated position to the loading position of said magazine, second electric motor means, means driven by said second electric motor means for indexing said magazine to bring said pin receiving openings successively into loading relation with said chute means, closure means controlling movement of pins from said chute means into said magazine, means driven by said second motor means for intermittently opening and closing said closure means, said last-mentioned means being timed to open said closure means only between indexing movements of said magazine, a third operating circuit for said second motor means, switch means in said third circuit for disabling said third circuit when said carriage moves away from its magazine loading position, switch means in said first circuit rendering said first circuit inoperative when said closure means are in other than closed position, and manually operable switch means for controlling each of said circuits.

8. A mechanical pin setter as set forth in claim 7 in which said valve means are electrically operable, a group of control circuits for selectively operating said valve means, and switch means rendering said group of control circuits inoperative when said carriage moves away from its pin setting position.

9. A mechanical pin setter as set forth in claim 7, a plurality of tiltably mounted mercury switches in said first and second circuits arranged when tilted in one direction to close the first of said circuits and open the second, and when tilted in the opposite direction to open the first of said circuits and close the second, and means operated by rotation of said reversible motor for tilting said mercury switches in one direction when said carriage reaches its pin setting position and for tilting the mercury switches in the opposite direction when the carriage reaches its magazine loading position.

10. A mechanical pin setter as set forth in claim 7 in which said switch means for deenergizing said first circuit when said carriage reaches said pin setting position and for deenergizing said second circuit when said carriage reaches said magazine loading position comprise two station-

ary normally closed switches positioned to be contacted and opened by said carriage on reaching said pin setting position and said magazine loading position, respectively.

- 5 11. A mechanical pin setter as set forth in claim 7 in which separable connector means are provided in the conduits leading from said piston devices of said second group to said door operating piston devices, said connector means comprising a stationary connector and a mating connector element carried by said carriage and adapted to engage said stationary element in fluid pressure transmitting relation only when said carriage is in its pin setting position.
- 15 12. In a mechanical bowling pin setting machine for use with a bowling alley, the combination of a pin magazine positioned above the alley, movable closure means cooperating with said magazine and normally retaining the pins in the magazine, power means for moving said closure means to pin releasing positions, pin receiving means located in the floor of the alley in the set positions of the pins and movable to elevated pin receiving positions, power means for moving said pin receiving means to said elevated positions, and means associated with both of said power means for assuring that said pin receiving means reach said elevated positions prior to the moving of said closure means to pin releasing positions.
- 25 13. In a mechanical bowling pin setting machine for use with a bowling alley, the combination of a pin magazine positioned above the alley, movable closure means cooperating with said magazine and normally retaining the pins in the magazine, first fluid pressure operable piston means associated with said closure means for moving said closure means to pin releasing positions to release said pins for downward movement toward their set positions, reciprocable pin receiving means positioned in the floor of the alley at the set positions of the pins and having normal positions flush with the alley surface and elevated pin receiving positions, second fluid pressure operable piston means associated with said pin receiving means for moving said pin receiving means to said elevated positions, and means preventing operation of said first-mentioned piston means until said last-mentioned piston means have substantially completed their pin receiver elevating movements, whereby pins are released from said magazine only after said pin receiving means reach their elevated positions.
- 35 14. In a mechanical bowling pin setting machine for use with a bowling alley, the combination of a pin magazine positioned above the alley, movable closure means cooperating with said magazine and normally retaining the pins in the magazine, first fluid pressure operable piston means associated with said closure means for moving said closure means to pin releasing positions to release said pins for downward movement toward their set positions, reciprocable pin receiving means positioned in the floor of the alley at the set positions of the pins and having normal positions flush with the alley surface and elevated pin receiving positions, second fluid pressure operable piston means associated with said pin receiving means for moving said pin receiving means to said elevated positions, a fluid pressure supply for said second piston means, and means for supplying fluid from said second piston means to said first piston means when said second piston means has substantially completed

its pin receiver means elevating stroke, whereby pins are released from said magazine only after said pin receiving means reach their elevated positions.

15. In a mechanical bowling pin setting machine for use with a bowling alley, the combination of a pin magazine positioned above the alley, movable closure means cooperating with said magazine and normally retaining the pins in the magazine, first fluid pressure operable piston means associated with said closure means for moving said closure means to pin releasing positions to release said pins for downward movement toward their set positions, reciprocable pin receiving means positioned in the floor of the alley at the set positions of the pins and having normal positions flush with the alley surface and elevated pin receiving positions, second fluid pressure operable piston means associated with said pin receiving means for moving said pin receiving means to said elevated positions, a fluid pressure supply for said second piston means, and means for supplying fluid from said second piston means to said first piston means including a port in said second piston means constructed and arranged to be uncovered to connect said first piston means with said fluid pressure supply upon substantial completion of the pin receiving means elevating stroke of said second piston, whereby pins are released from said magazine only after said pin receiving means reach their elevated positions.

16. In a mechanical pin setter for use with bowling alleys, the combination of a movable carriage mounted above the rear end of the alley, a pin magazine mounted on said carriage, means mounting said carriage and magazine for movement between a magazine loading position and a pin setting position, power means for so moving said carriage and magazine, pin receiving means in the alley at the set positions of the pins, means mounting said pin receiving means for movement between normal lowered positions flush with the alley surface and elevated pin receiving positions, and interlock means rendering said power means inoperative to move said carriage and magazine from said pin setting position as long as one or more of said pin receiving means is in other than its normal lowered position.

17. The structure of claim 16 in which said power means includes an electrical power device and a control circuit for said power device, and in which said interlock means includes electrical switch means in said circuit and positioned to be maintained in closed circuit condition by said pin receiving means when said pin receiving means are in their normal lowered positions.

18. In a mechanical pin setter for use with a bowling alley, the combination of a movable carriage mounted above the rear end of the alley, a pin magazine mounted on said carriage, means mounting said carriage and magazine for movement between a magazine loading position and a pin setting position, pin receiving means in the alley at the set positions of the pins, means

mounting said pin receiving means for movement between normal lowered positions flush with the alley surface and elevated pin receiving positions, power means for effecting elevation of said pin receiving means to said elevated positions, and interlock means controlled by said carriage for rendering said power means inoperative when said carriage and magazine are in other than said pin setting position.

19. The structure of claim 18 in which said power means includes electrical control means and an operating circuit for said control means, and in which said interlock means includes normally open switch means in said circuit positioned to be closed by said carriage when said carriage is in its pin setting position.

20. The structure of claim 18 in which said power means includes a fluid pressure operable piston, electrically operable valve means for controlling the flow of fluid to said piston, and a control circuit for said electrically operable valve means, and in which said interlock means includes normally open switch means in said circuit positioned to be closed by said carriage when said carriage is in its pin setting position.

21. A mechanical pin setter as set forth in claim 1, said means for discharging pins from the magazine being operable in response to movement of said receivers to their elevated positions.

22. In a mechanical bowling pin setting machine, the combination set forth in claim 12, wherein said pin receiving means normally have their upper surfaces flush with the alley surface, and means for returning said pin receiving means from their elevated positions from their normal positions, thereby to position the pins in their set positions.

23. In a mechanical bowling pin setting machine, the combination set forth in claim 12, wherein said pin receiving means have hollow upper ends, flat surfaced means mounted in said hollow upper ends, means for positioning said flat surfaced means flush with the alley surface when said pin receiving means are in their normal, lowered positions and for releasing said flat surfaced means for movement to positions spaced a short distance below the upper ends of said pin receiving means when the pin receiving means are in their elevated pin receiving positions.

JOURNEY F. TIMBERLAKE.
